UNITED STATES PATENT OFFICE

JOHN IRVING NASMITH, OF ELTHAM, LONDON, AND WILFRED KIRBY, OF BARNES, LONDON, ENGLAND, ASSIGNEES TO VICKERS-ARMSTRONGS LIMITED, OF LONDON, ENGLAND, A BRITISH COMPANY

FEEDING OF SHEETS OF CARDBOARD OR OTHER MATERIAL

Application filed July 12, 1929, Serial No. 377,706, and in Great Britain August 31, 1928.

This invention relates to the feeding of sheets of cardboard or other material, and more particularly to the feeding of sheets singly from a pile of sheets.

Various forms of sheet feeding devices have been proposed in which the top sheet of the pile is propelled forwardly by frictional contact with one or more rubber covered discs or the like. With such devices, however, difficulties have been experienced owing to the uncertainty of the top sheet releasing itself from the rest of the pile, and the object of the present invention is to overcome these difficulties, and to ensure that the top sheet shall be given positive displacement relatively to those underneath.

According to the invention the top sheet of the pile is fed forwardly under the influence of one or more (preferably two) propelling members which engage the rear edge of the sheet and the upper surface of the sheet in the vicinity of its rear edge, and a holding-down or guiding member which engages the upper surface of the sheet at or near its forward edge. The sheet is passed through a gap which is arranged contiguous to the forward edge of the top sheet. The upper wall of such gap may be constituted by the lower surface of the holding-down member and the lower wall of such gap may be formed by the upper surface of a vertically disposed bottom plate or blade arranged so as to bear against the forward end of the pile. The upper surface of such blade is preferably of convex formation and the width of the gap at its narrowest part may be slightly greater than the thickness of the material being fed but is preferably of the order of one and one-half times the thickness of such material. The holding-down member is preferably slidably mounted and so interconnected with the propelling member or members that it is moved forwardly at the same speed as that of the sheet and, if desired, the lower surface of the holding-down member may be roughened or serrated to enable it to assist in the movement of the sheet. To enable the sheets constituting the pile to be fed successively the propelling member or members and the holding-down member are given a reciprocating movement

in a horizontal or substantially horizontal plane, which movement may be derived from any suitable source.

The pile of sheets may be mounted upon a table or support and means may be provided for raising the table as the pile diminishes. In order, however, to ensure that the gap shall always be opposite the top sheet of the pile the members forming the gap may be carried by a suspended framework which is adapted to rise and fall as the level of the top sheet rises and falls. For this purpose the part in which the holding-down member is slidably mounted and the bottom blade may be secured to a pair of parallel cross bars having their ends secured to a pair of vertical rods arranged one at each side of the machine, the upper ends of such rods being suspended from a pair of substantially horizontal pivotally mounted levers. The said levers may be provided with suitable balance weights so that the turning moment produced on the levers by the framework consisting of the vertical rods and the parts carried thereby, exceeds that produced by the counter-weights by an amount which is just sufficient to keep the upper wall of the gap or the lower surface of the holding-down member in contact with the top sheet of the pile. By mounting the holding-down member in this fashion the pressure applied to the top of the pile is reduced to a minimum and the drawbacks attendant upon those forms of feeding devices which rely upon the application of considerable pressures to the top of the pile are overcome.

In order that the said invention may be clearly understood and readily carried into effect, the same will now be described more fully with reference to the accompanying drawings, in which:—

Figure 1 is an elevation of one embodiment of the invention;

Figure 2 is a side view, looking in the direction of the arrow A, of the arrangement illustrated in Figure 1, the pile of sheets shown broken away in the left hand part of the view in order to show the position of the bottom blade;

Figure 3 is an enlarged view of the sus-

pended framework by which the holding-down member and other parts are carried, and

5 Figure 4 is an enlarged end view showing the relative position of the holding-down member and the bottom blade.

10 *a, a* are the propelling members each of which consists of a narrow block having a flat underneath surface for engagement with the upper surface of the top sheet of the pile *b* and a downwardly projecting finger *c* for engagement with the rear edge of such sheet, the said fingers being adjustably secured to the rear edges of the blocks by screws *d* so 15 that the fingers may be raised or lowered according to the thickness of the sheets to be fed. *e* is the holding-down or guiding member which is adapted to engage the upper surface of the sheets to be fed in the vicinity 20 of their forward edges and consists of a narrow slidably mounted bar the underneath surface of which is preferably formed with serrations *f* to enable it to assist in the feeding of the sheets.

25 The means by which the holding-down member is reciprocated comprise a pair of rocking arms *g* which are mounted above the pile with their free and lower ends connected by a cross bar *h* extending transversely of the direction of feed. The rear end of the holding-down member is formed with a vertical slot *i* and the arrangement is such that the cross bar *h* engages the side walls of the slot and an oscillatory or swinging movement of the 30 rocking arms will cause a reciprocating movement of the holding-down member, the rise and fall of the cross bar *h* due to the swinging of the arms *g* being accommodated by the vertical slot *i*. To enable the propelling members *a* to move in unison with the holding-down member *e* they are mounted on the 35 rear ends of a pair of rearwardly extending rods *j* the forward ends of which are secured to, or pivotally mounted on, the cross bar *h*. 40 The said propelling members are preferably 45 adjustably mounted, for instance, by the aid of screws *k*, on the rods *j* so as to permit the position of the propelling members to be varied in accordance with the length of the 50 sheets being fed. Also, the rods *j* may have one or more counter-weights *l* adjustably mounted thereon. The upper ends of the 55 rocking arms *g* are secured to a sleeve *m* which is rotatably mounted on a shaft *n* which is mounted in position in the framework of the machine above the pile so that it extends transversely of the direction of feed.

60 *o* is the gap through which the sheets are fed at the forward end of the machine and 65 the upper wall of which is constituted by the lower surface of the holding-down member. The lower wall of the gap is formed by the upper surface of the vertically disposed bottom blade or plate *p* which is arranged so that it bears against the forward end of the pile and

70 the width of which is substantially the same as that of the holding-down member. The upper surface of the blade is of convex formation as may be seen from Figures 2, 3 and 4, and the tip or the upper end of the blade is bent or formed so that it is curved slightly out of the vertical towards the rear end of the machine. By forming the upper end of the blade in this fashion the sheets will each in turn be given a slight backward movement as 75 they approach the top of the pile. It has been found that this facilitates the feeding of the sheets through the gap and tends to prevent the top sheet from adhering to the one below. The feeding of the sheets through the gap 80 may be further facilitated by causing their forward edges to be inclined upwardly. In order to produce this result the forward edge of the table or support on which the pile rests 85 may be provided with a curved or inclined face *q*.

90 The forward edges of the sheets constituting the pile may rest against a vertical stack plate *r* which may be formed with a cut away portion *s* to allow relative movement to take place between the stack plate and the bottom blade *p*.

95 As mentioned above the holding-down member and the parts associated therewith are preferably carried by a suspended framework so that pressure on top of the pile is reduced to a minimum. In the arrangement illustrated, the holding-down member *e* is slidably mounted in a member *t* which is secured to a cross bar *u* and the bottom blade *p* is secured to another cross bar *v* which is parallel to the cross bar *u*, the said cross bars being secured at their ends to a pair of vertical rods *w* arranged one at each side of the machine and the upper ends of the rods *w* 100 being suspended from a pair of substantially horizontal levers *x* which are pivoted on the transverse shaft *n*. The levers *x* are provided on the opposite sides of their pivots with balance weights *y* which are adjusted so that 105 the turning moment produced on the levers by the framework consisting of the vertical rods *w* and the parts carried thereby exceeds that produced by the counter-weights *y* by an amount which is just sufficient to keep the 110 lower surface of the holding-down member in contact with the top sheet of the pile. By this arrangement the holding-down member more or less "floats" on the upper surface 115 of the pile and will rise and fall as the level of the top sheet of the pile rises and falls so as to ensure that the gap shall always be opposite such top sheet.

120 The invention is particularly applicable to 125 feeding mechanisms for rotary scoring and cutting machines for the preparation of carton blanks but it will be understood that it may readily be applied to feeding mechanisms for other machines into which it is 130

required to feed sheets singly from a pile of sheets.

What we claim and desire to secure by Letters Patent of the United States is:—

- 5 1. A sheet feeding device comprising a propelling member adapted to engage the rear edge of the sheet to be fed, a holding-down or guiding member adapted to engage the upper surface of the sheet in the vicinity of its forward edge, means for reciprocating the propelling and holding-down members, and a bottom blade spaced a short distance from the lower surface of the holding-down member, the upper surface of the bottom blade being 10 of convex formation and curved so as to deflect the top sheets of the pile backwardly.
2. A sheet feeding device comprising a propelling member adapted to engage the rear edge of the sheet to be fed, a slotted holding-down or guiding member adapted to engage the upper surface of the sheet in the vicinity of its forward edge, and means for reciprocating the propelling and holding-down members comprising a pair of rocking 15 arms interconnected by a cross bar which is 20 slidable in the slot formed in the holding-down member and rods extending rearwardly from the said cross bar, the propelling members being carried by the said rods.
3. A sheet feeding device comprising a propelling member adapted to engage the rear edge of the sheet to be fed, a holding down or guiding member constituting the upper surface of a gap through which the sheet passes, 25 which surface is adapted to move with the sheet and to engage the upper surface thereof in the vicinity of its forward edge and means for moving the propelling and holding down members.

- 40 4. A sheet feeding device for feeding sheets singly from a pile of sheets comprising a propelling member consisting of a narrow block having a flat underneath surface for engagement with the upper surface of the top sheet 45 of the pile and a downwardly projecting finger for engagement with the rear edge of such sheet, a holding down or guiding member constituting the upper surface of a gap through which the sheet passes and which is adapted to move with the sheet and to engage the upper surface thereof in the vicinity of its forward edge and means for moving the propelling and holding down members.

5. A sheet feeding device comprising a propelling member adapted to engage the rear edge of the sheet to be fed, a holding down or guiding member consisting of a slidably mounted bar having a roughened or serrated underneath surface constituting the 55 upper surface of a gap through which the sheet passes and which is adapted to move with the sheet and to engage the upper surface thereof in the vicinity of its forward edge and means for reciprocating the propelling and holding down members.

6. A sheet feeding device for feeding sheets singly from a pile of sheets comprising a propelling member adapted to engage the rear edge of the sheet to be fed, a holding down or guiding member constituting the upper surface of a gap through which the sheet passes and which is adapted to move with the sheet and to engage the upper surface thereof in the vicinity of its forward edge, means for reciprocating the holding down and propelling members and means whereby the holding down and propelling members can be reciprocated in unison.

7. A sheet feeding device comprising a propelling member adapted to engage the rear edge of the sheet to be fed, a holding down or guiding member constituting the upper surface of a gap through which the sheet passes and which is adapted to move with the sheet and to engage the upper surface thereof in the vicinity of its forward edge, means for reciprocating the propelling and holding down members, a framework by which the said holding down member is carried and a counter-weight on the said framework, the said framework being suspended so that the turning moment produced by the framework exceeds that produced by the counter-weight by an amount which is just sufficient to keep the lower surface of the holding down member in contact with the top sheet of the pile.

8. A sheet feeding device comprising a propelling member adapted to engage the rear edge of the sheet to be fed, a holding down or guiding member constituting the upper surface of a gap through which the sheet passes and which is adapted to move with the sheet and to engage the upper surface of the sheet in the vicinity of its forward edge, a vertically disposed bottom blade spaced a short distance from the lower surface of said holding down member and constituting the lower surface of said gap and means for reciprocating the propelling and holding down members.

9. A sheet feeding device comprising a propelling member adapted to engage the rear edge of the sheet to be fed, a holding down or guiding member constituting the upper surface of a gap through which the sheet passes and which is adapted to move with the sheet and to engage the upper surface thereof in the vicinity of its forward edge, a vertically disposed bottom blade spaced a short distance from the lower surface of the holding down member and constituting the lower surface of said gap, a framework carrying said holding down member said framework being suspended so that the space between the holding down member and the bottom blade is always maintained opposite the top sheet of the pile, and means for reciprocating the propelling and holding down members.

10. A sheet feeding device for feeding sheets singly from a pile of sheets comprising

- propelling members adapted to engage the rear edge of the sheets to be fed, a holding down or guiding member constituting the upper surface of a gap through which the sheet passes and which is adapted to move with the sheets and to engage the upper surface thereof in the vicinity of its forward edge, means for reciprocating the propelling and holding down members and means for maintaining the holding down and propelling members in engagement with the top sheet of the pile.
11. A sheet feeding device for feeding sheets singly from a pile of sheets, comprising a table on which the pile of sheets rests, propelling members for engagement with the rear edge of the top sheet of the pile, a holding down and guiding member constituting the upper surface of a gap through which the sheet passes and which is adapted to move with the sheet and to engage the upper surface thereof in the vicinity of its forward edge, means for reciprocating the propelling and holding down members and means for maintaining the holding down and propelling members in engagement with the top sheet of the pile, the forward edge of the table constituting the lower surface of said gap being inclined or curved in an upward direction.
12. A sheet feeding device for feeding sheets singly from a pile of sheets comprising propelling members adapted to engage the rear edge of the sheet to be fed, a holding down or guiding member constituting the upper surface of a gap through which the sheet passes and which is adapted to move with the sheet and to engage the upper surface thereof in the vicinity of its forward edge and means for reciprocating the holding down and propelling members, said holding down member being suspended and counterweighted so that it is maintained in contact with the top sheet of the pile without exerting considerable pressure thereon.
13. A sheet feeding device comprising a propelling member adapted to engage the rear edge of the sheet to be fed, a holding down or guiding member constituting the upper surface of a gap through which the sheet passes and which is adapted to move with the sheet and to engage the upper surface of the sheet in the vicinity of its forward edge a bottom blade spaced a short distance from the lower surface of said holding down member and constituting the lower surface of said gap the upper surface of the bottom blade being of convex formation and curved so as to deflect the top sheet of the pile backwardly and means for reciprocating the propelling and holding down members.
